REMOTE CONTROLLING APPARATUS

Alfred B. Miller, Edgewood, Pa., assignor to The Union Switch & Signal Company, Swissvale, Pa., a corporation of Pennsylvania

Application October 9, 1929, Serial No. 398,343
Renewed November 2, 1935

55 Claims. (Cl. 246—3)

My invention relates to remote controlling apparatus, and particularly to apparatus of the type comprising a plurality of communication channels extending between two spaced points, 5 together with means for selectively controlling such channels individually or in combination to produce distinctive code elements for transmitting signals from one point to another. Apparatus embodying my invention is suitable for, 10 though in no way limited to, use in a centralized traffic controlling system for railroads adapted for controlling a plurality of train governing devices, such as railway switches, or signals, or both, from a remote point such, for example, as 15 a train dispatcher's office; and for also communicating to said office the condition of such devices and other information, such as the presence of trains adjacent such devices.

The apparatus of my invention is an improvement upon that disclosed in the several applications herein referred to, and also upon that disclosed in the following pending applications for Railway traffic controlling apparatus: H. A. Wallace, Serial No. 125,659, filed July 29, 1926; 20 L. V. Lewis, Serial No. 254,690, filed February 16, 1928; and G. W. Baughman, Serial No. 255,375, filed February 18, 1928. It is also an improvement upon that disclosed in the pending Lewis application, Serial No. 291,465, filed July 9, 1928, for Remote controlling apparatus.

In systems of the type described, it is customary to supply control codes to a line circuit or line circuits extending between the dispatcher's office and the remote point at which the governing devices are located for effecting the control of these devices, and to deliver indication codes to this line circuit or to these line circuits from the remote point for informing the dispatcher concerning the condition of the devices. In at 40 least one system which has been previously suggested, the codes employed for these purposes are made up of code elements having different characters which separately actuate individual receiving devices, and apparatus is also provided which is selectively responsive to the sequence of operation of these receiving devices. In my present invention I utilize apparatus which is responsive to the sequence in which code elements of different characters are received, but I prefer 45 to employ receiving devices which are controlled directly from the point at which the control code or indication code originates. In a preferred embodiment of my invention I provide a plurality of line circuit or indication channels 50 extending from the dispatcher's office to each

of the remote points at which it is desired to operate governing devices, certain of which circuits or channels may have a common return wire. With this arrangement it will be apparent that I can produce code elements of different 5 characters by supplying impulses to different line circuits, and that I can produce code elements having still other characters by supplying impulses simultaneously to combinations of these line circuits. 10

I will describe one form of remote controlling apparatus embodying my invention, and will then point out the novel features thereof in claims.

In the accompanying drawings, Figs. 1 and 2 when placed end to end with Fig. 1 on the left 15 form a diagrammatic view showing one form of remote controlling apparatus embodying my invention. Fig. 1 illustrates the apparatus located at the dispatcher's office, and Fig. 2 illustrates the apparatus located at a remote point.

Similar reference characters refer to similar 20 parts in both views.

Referring now to the drawings, it will be seen that three line wires, designated by the reference characters 1, 2 and 3 extend from the dispatcher's office to each of the remote stations controlled from this office. Line wire 3 serves as a common return for two line circuits, one including line wire 1 and the other including line wire 2. Two line relays are located at the dispatcher's office and two similar line relays 25 are located at each remote station, each designated by the reference character R with a prefix corresponding to the location and a suitable distinguishing suffix. Each line relay is included in series in one of the line circuits made up of the common wire 3 and one of the line wires 1 or 2. For example, at the dispatcher's office, line relay AR1 is included in series with line wire 1. Current is normally supplied to 30 both line circuits from batteries each designated by the reference character 4 with a suitable distinguishing exponent and one located at the dispatcher's office and at each remote station. Since both line circuits are normally closed, it 35 follows that all line relays R are normally energized. 40

For the purpose of delivering control codes to the line circuits, the dispatcher's office is provided with a plurality of panels, one for each remote 50 station which is to be controlled from the dispatcher's office, and each panel is provided with manually controlled switching devices for separately controlling governing devices at the associated station. Referring particularly to panel 55

B on Fig. 1, this panel is provided with two switching devices BE1 and BE2 each comprising a lever 12, which as here shown is in the form of a cam which operates a cam follower 13. The lever 12 also controls a movable contact 14 which may be moved into engagement with a selected one of a plurality of fixed contacts. The switching devices BE1 and BE2 jointly control a movable member 18 which is pivoted at point 18^a and 10 which is arranged to swing in a clockwise direction about point 18^a when either switching device is operated. When the member 18 is operated, contact arm 20 is moved out of engagement with contact 22 which it normally engages, and is 15 swung into engagement with contact 24. This movement of arm 20 permits a latch 23 to drop under the influence of gravity to a position in which the return of arm 20 is prevented.

Each panel is also provided with a code setting 20 relay, designated by the reference character W with a prefix corresponding to the panel, and having a winding 25 which controls a finger 24 and a plurality of contacts. When winding 25 of relay BW is energized, the finger 24 is swung to the 25 left and the tip of this finger then engages the arm 20 and at the same time lifts the latch 23. Under these conditions therefore the arm 20 is unlatched, but is held in its left-hand position, so that contact 20-24 is closed, until winding 25 30 is de-energized.

The switching device BE1 may be employed as a switch lever to operate a railway switch at one of the remote stations, and when the lever 12 of switching device BE1 occupies the normal position 35 shown in the drawings, contact 14-16 is closed. If the lever is operated to its reverse position, however, contact 14-15 becomes closed. The switching device BE2 may be utilized as a signal lever to govern railway signals at the same 40 station and when lever 12 of switching device BE2 occupies the normal position illustrated in the drawings, contact 14-16 is closed. If lever 12 is swung to the left, contact 14-15 is closed, and if lever 12 is swung to the right, contact 14-17 45 is closed.

For the purpose of delivering code elements to the line circuits I have provided transmitting relays at the dispatcher's office and at each remote station. Referring for example to Fig. 1, I have 50 shown three transmitting relays AT1, AT2 and AT3. Relay AT1 has a back contact 38 normally included in the line circuit including line wires 1 and 3 so that when this relay is energized, relay AR1 is de-energized and line 1 is opened. In 55 similar manner the opening of back contact 39 of relay AT2 de-energizes relay AR2 and opens line wire 2. When relay AT3 is energized, the opening of back contacts 40 and 41 de-energizes both line relays AR1 and AR2 and opens both line 60 wires 1 and 2.

The transmitting relays AT1, AT2 and AT3 and the corresponding relays at each station are operated in different sequences to produce different control codes, each made up of a plurality 65 of code elements during which one or more of the line circuits is open. The transmitting relays at the dispatcher's office are controlled in part by the switching devices E on the control panels at the dispatcher's office and also by a 70 group of relays, one function of which is to prevent interference between codes originating at different stations. The transmitting relays at each location are also controlled by a stepping contactor similar in all respects to the stepping contactor 75 which is described and claimed in an

application for Letters Patent, Serial No. 362,948, filed by Clarence S. Snavely on May 14, 1929, for Remote controlling apparatus. Referring particularly to the apparatus at the dispatcher's office, stepping contactor P^A comprises a spider 5 26 operated by a pawl 65 driven by a magnet F^A. This spider co-operates with a plurality of fixed contact segments designated by the reference characters 27 to 34 and arranged in such manner that an arm of the spider engages one of these 10 segments at all times. As shown in the drawings, the spider engages segment 27. If, now, the magnet F^A is energized, pawl 65 is moved along one tooth on the spider 26 and when the magnet F^A is next de-energized, the spider 26 is advanced 15 one step so that an arm of the spider then engages contact 28. In similar manner successive energizations and de-energizations of the stepping magnet F^A advance the spider 26 from each segmenting of the stepping contactor to the next segment in order. 20

The apparatus herein shown and described may be utilized for controlling governing devices of any suitable type, but for purpose of explanation, I have illustrated at station B a section of 25 railway track 5-6 provided with a switch 7 leading into a siding 8. The section 5-6 is provided with a track circuit including a battery 9 connected across the rails adjacent one end of the section and a track relay v connected across 30 the rails adjacent the other end of the section. The switch 7 is controlled by a motor g comprising an armature 10 and a field 11, which motor is controlled in part by two switch relays p¹ and p². Switch 7 in turn controls a pole-changer 35 35 which governs the polarity of current supplied from terminals B and C of a suitable source of energy to an indication relay k as will be apparent from the drawings. Relay k is energized in the normal direction, so that its polar contacts 40 are swung to the left, when switch 7 occupies its normal position. When the switch 7 occupies its reverse position, however, relay k is energized in the reverse direction so that its polar contacts are 45 swung to the right. When switch 7 occupies an intermediate position, indication relay k is de-energized so that its front contacts are open. Switch 7 also controls two contacts 36 and 37. Contact 36 is closed at all times except when the switch occupies its normal position and contact 37 is closed at all times except when the switch occupies its reverse position. Furthermore, contact 94-94^a is closed only when the switch occupies 50 its normal position and contact 94-94^b is closed only when the switch occupies its reverse 55 position.

Eastbound traffic through the section 5-6 is controlled by two signals w¹ and w² which, as here shown, are mounted on the same mast. In similar manner westbound traffic is controlled by two 60 signals w³ and w⁴. The signals w¹ and w², w³ and w⁴ are controlled in part by two signal relays q¹ and q².

The switching relays p¹ and p² and the signal relays q¹ and q² at station B are controlled by 65 receiving apparatus which will be described in detail hereinafter.

As shown in the drawings, the switching devices BE1 and BE2 on panel B at the dispatcher's office occupy their normal positions and switch 7 at 70 station B occupies its normal position. Switch relays p¹ and p² are both de-energized and the signal relays q¹ and q² are also de-energized so that all signals at station B occupy their stop 75 positions.

In explaining the operation of the apparatus as a whole, I will first assume that the dispatcher wishes to reverse switch 7 at station B. In order to accomplish this result, he moves the switch 5 lever 12 of switching device BE1 to the reverse position. As a result the corresponding cam follower 13 is moved to the left, thereby swinging member 18 to the left and closing contact 20-21. At the same time contact 19 is opened. Latch 10 23 now engages the arm 20 and holds this arm in engagement with contact 21. When the lever 12 has reached its full reverse position, member 18 returns to the position in which it is shown in the drawings, thereby closing contact 19, but contact 20-21 remains closed because of latch 23.

Under normal conditions a starting relay L^A is energized, current flowing to this relay from terminal B of a suitable source of energy over 20 back contact 42 of relay AS, back contact 43 of relay VA, contact 44-44^a of master relay J^A, resistor 45, contact 20-22 of panel B, and thence through corresponding contacts on each of the remaining panels, and winding of relay L^A, back 25 to terminal C of the same source. The operation of the switching device BE1, just described, interrupts the normal circuit for relay L^A so that this relay becomes de-energized. The closing of back contact 48 of relay L^A, completes a pick-up circuit for relay AS which may be traced from terminal B over front contact 46 of relay Q^A, winding of relay AS, back contact 47 of relay K^A, and back contact 48 of relay L^A to terminal C. Relay Q^A is controlled by line relays AR1 and 30 AR2 so that relay Q^A is energized when both line relays are closed which is, of course, the normal condition of the apparatus when no codes are being sent. The circuit for relay Q^A includes front contacts 58 and 59 of relay AR1 and front 35 contact 60 of relay AR2. Relay AS therefore becomes energized over the circuit just traced, and when the front contacts of this relay become closed a branch is completed around front contact 46 of relay Q^A from terminal B over front 40 contact 51 of relay AS to the right-hand terminal of relay AS. This branch comprises a stick circuit for relay AS which holds the relay in its energized condition after relay Q^A opens as will be described below.

When relay AS becomes energized, the opening of back contact 49 opens line wire 1 and the opening of back contact 50 opens line wire 2; it follows therefore that both line relays at each 45 of the remote stations are de-energized. At the dispatcher's office, however, the energization of relay AS completes branch circuits for the line relays AR1 and AR2 over which these relays are supplied with energy from battery 4^A and the 50 latter relays remain closed. A circuit is now completed, however, for relay M^A from terminal B over front contact 42 of relay AS, winding of relay M^A and back contact 52 of relay L^A to terminal C. Relay M^A therefore becomes energized, whereupon a stick circuit is completed 55 for this relay including its own front contact 53 and back contact 52 of relay L^A as will be obvious from the drawings. The energization of relay M^A also completes a circuit for transmitting relay AT3 which circuit may be traced from terminal B over front contact 53 of relay M^A, back contact 56 of stepping magnet F^A, contact 26-27 of stepping contactor P^A and winding of relay AT3 to terminal C. When relay AT3 becomes energized, 60

the local circuits for both relays AR1 and AR2 are interrupted at back contacts of relays AT3 so that both line relays become de-energized and de-energize relay Q^A.

When relay Q^A becomes de-energized, current 5 is supplied over back contact 46 of this relay to relays H^A and K^A in parallel so that these relays both become energized. The operation of relay H^A is of no particular significance at this point in the sequence of operation, but relay K^A opens 10 the stick circuit for relay AS and completes a snubbing circuit for this relay which may be traced from terminal B over front contact 51 of relay AS, winding of relay AS, front contact 47 of relay K^A and resistor 55 to terminal B. When 15 the snubbing circuit is closed, it will be seen that both terminals of relay AS are connected with the same terminal of the source and at the expiration of an interval of time, relay AS opens its front contacts. The releasing of relay AS restores 20 the normal line circuits over back contacts 49 and 50, but relay AT3 is now energized so that the line circuits are held open.

Furthermore, the releasing of the relay AS completes a pick-up circuit for code-setting relay 25 BW of panel B, current flowing from terminal B, over back contact 42 of relay AS, back contact 43 of relay VA, contact 44-44^a of relay J^A, resistor 45, contact 20-21 of switching device BE1, contact 19, winding 25 of code-setting relay BW, 30 winding of reset relay a, and front contact 55 of relay M^A to terminal C. The reset relay a therefore becomes energized and the code setting relay BW is also energized to draw finger 24 into engagement with arm 20. The finger 24 releases latch 23, but contact 20-21 is now held closed by the finger 24. With finger 24 of code-setting relay BW in this position, however, contact 20-24 is closed and a circuit is completed for the right-hand winding of master relay J^A by means of 35 which this winding is connected across resistor 45. This circuit may be traced from one terminal of resistor 45, through contact 44-44^a of master relay J^A, right-hand winding of relay J^A, finger 40 45 of code-setting relay BW, contact arm 20, and thence to the other terminal of resistor 45. The potential drop across the resistor 45 is sufficient 45 to operate the master relay J^A, and contact 44-44^a of this relay now opens and contact 50 50 50 closes.

One result of this operation of master relay J^A is that the opening of contact 44-44^a opens all 55 circuits for the remaining code-setting relays CW, etc., and prevents the operation of any additional code-setting relay until the relay BW has become de-energized and the apparatus restored to its normal condition.

Another result of the operation of master relay J^A is that relay b now becomes energized. The 60 circuit for relay b passes from terminal B over back contact 42 of relay AS, back contact 43 of relay VA, contact 44-44^b of relay J^A, and winding of relay b to terminal C. When relay b becomes energized, current flows from terminal B over front contact 56 of relay b, back contact 57 of relay D^A, and winding of stepping magnet F^A to terminal C. The stepping magnet F^A therefore becomes energized, advancing 65 the pawl 65 one tooth, and disconnecting the spider 26 from terminal B at back contact 54 of magnet F^A. It will be remembered that the transmitting relay AT3 was energized over contact 26-27 of the stepping contactor P^A, so that 70 75

relay AT3 now becomes de-energized, thereby restoring the line circuits and allowing relays AR1 and AR2 to become energized provided the associated line circuits are closed at all other stations. This, of course, energizes relay Q^A and opens the circuits for relays H^A and K^A. The two latter relays, however, have slow-acting characteristics, so that these relays bridge the brief intervals of time during which relay Q^A is de-energized during the transmission of codes and relays H^A and K^A remain picked up until the completion of the code.

The equipment at the dispatcher's office is now in condition for the transmission of a control code, and this takes place as follows:

When the stepping magnet F^A became energized, a circuit was completed for relay D^A over front contact 53 of relay M^A and front contact 54 of magnet F^A. Relay D^A therefore becomes energized and opens, at back contact 57 thereon, the circuit previously described for magnet F^A. As a result, magnet F^A becomes de-energized, and when this happens, the pawl 65 advances the spider 26 one step into a position in which contact 26-28 is closed. Each time spider 26 engages one of the segments 28 to 33, one of the transmitting relay AT1, AT2 or AT3 is energized, the particular one of these relays which is picked up depending upon the code which it is desired to transmit and which is determined by the contacts of the code-setting relay which is energized and the position of the switching devices associated therewith. For convenience in connecting the various parts, the segments of the stepping contactor are brought out to bus bars, and the terminals of the transmitting relays are also brought out to bus bars, cross connections being provided between these two sets of bus bars to produce any desired code arrangement as shown in the drawings.

Relay AT2 becomes energized when contact 26-28 of stepping contactor P^A is closed, the circuit for this relay passing from terminal B over front contact 53 of relay M^A, back contact 54 of magnet F^A, contact 26-28 of stepping contactor P^A, contact 66 of code setting relay BW, and winding of relay AT2 to terminal C. When relay AT2 picks up, line wire 2 is interrupted to produce the first element of a control code. When magnet F^A became de-energized to complete the circuit just traced, relay D^A became de-energized, and when relay D^A releases, the circuit for magnet F^A again becomes closed, energizing the magnet and advancing the pawl 65 another step, thereby interrupting the circuit through contact 26-28 of contactor P^A. Relay AT2 therefore becomes de-energized and closes the line circuit to terminate the first code element.

When relay F^A becomes energized, it completes the circuit for relay D^A, which then interrupts at back contact 57, the circuit for magnet F^A, and magnet F^A again becomes de-energized to close its back contact 54. When this happens, terminal B is again connected with spider 26 which has been moved into engagement with segment 29 and one of the transmitting relays is now energized to deliver the second element of the code. In the particular example here illustrated, the second element of the code is produced by energizing relay AT3 to open both line wires 1 and 2. The operation just described is repeated, and the stepping contactor P^A closes its contacts 75 in order, so that selected code elements are deliv-

ered in a predetermined sequence in accordance with the particular code-setting relay which is energized, and the position of the associated levers 12, as will be readily understood without further explanation.

As will be described more in detail hereinafter, the first elements of each control code are utilized to select a particular remote station, and the number of elements required for this purpose depends, of course, upon the number of remote stations which are to be controlled. In the present example, I have provided four elements in each code for the purpose of selecting a station and it will be apparent that with this arrangement, since there are three characters of code 15 elements, 81 stations may be controlled from the dispatcher's office. The code elements following these four station selecting elements are produced by operation of selected ones of the transmitting relays, in accordance with the function which is 20 to be performed at the station. Thus, since contact 14-15 of switching device BE1 is closed, the fifth or switch controlling element of the control code now being delivered to the line circuit and produced while contact 26-32 of stepping contactor is closed, results from the energization of relay AT2. In similar manner, since contact 14-16 of switching device BE2 is closed, the final or signal controlling element of the code is produced by energizing relay AT3.

After the final impulse of the control code, the next operation of the stepping contactor P^A brings spider 26 into engagement with segment 34. When this happens, a circuit is completed for relay V^A which may be traced from terminal B 35 over front contact 53 of relay M^A, back contact 54 of relay F^A, contact 26-34 of stepping contactor P^A, and winding of relay V^A to terminal C. When relay V^A becomes energized, the opening of back contact 43 disconnects the contact 44 40 of master relay J^A from terminal B, and the closing of front contact 43 of relay V^A completes a circuit for the left-hand winding of the master relay from terminal B over back contact 42 of relay AS, front contact 43 of relay V^A, and left- 45 hand winding of master relay J^A to terminal C. Relay J^A thereupon opens contact 44-44^b and closes contact 44-44^a. This operation of the master relay de-energizes relay BW, relay b and relay a. When relay BW releases, the finger 24 50 returns to its right-hand position, thereby allowing contact 22-20 to close. The releasing of relay b interrupts the circuit for magnet F^A so that when relay D^A next becomes de-energized, magnet F^A will remain de-energized for a brief 55 interval of time during which the spider 26 will pause in contact with segment 34.

It will be remembered that while a control code is being transmitted, relays H^A and K^A are energized during the periods of open circuit of one 60 or more of the line wires when either or both of relays AR1 or AR2 are open, and are deenergized when both line circuits are closed, but due to their slow-release characteristics these relays remain picked up until the completion of the code. 65 When the spider 26 pauses on segment 34, as explained above, the line circuits both remain closed, relays K^A and H^A are deenergized and relay H^A releases at the end of its time interval. Relay K^A has a somewhat longer holding time 70 than relay H^A and does not release until the expiration of a further time interval. When relay H^A releases, a circuit is closed for magnet F^A from terminal B over back contact 42 of relay AS, front contact 62 of relay M^A, front contact 75

63 of relay V^A , back contact 64 of relay H^A , back contact 57 of relay D^A , and winding of relay F^A to terminal C. Magnet F^A therefore becomes energized, and opens the circuit previously traced 5 for relay V^A . Furthermore, relay D^A now becomes energized, thereby again de-energizing magnet F^A and causing the spider 26 to be advanced into engagement with segment 27 thus returning the stepping contactor to its starting position.

10 The closing of back contact 43 of relay V^A completes the normal circuit previously traced for relay L^A , and relay L^A picks up, thereby de-energizing relay M^A at back contact 52 of relay L^A . In the meantime relay K^A has released and 15 since magnet F^A and relays D^A , H^A , V^A and M^A are de-energized, the apparatus is now restored to its normal condition. It should be pointed out that if a switching device has been operated during the delivery of the control code, the de- 20 energizing of relay V^A at the conclusion of this code will not pick up relay L^A , but the code-setting relay for such operated switching device will then become energized and the apparatus at the dispatcher's office will operate to transmit the 25 control code corresponding to the switching device which has been operated, in the same manner as just described in connection with the operation of switching device BE^1 .

For example, I will assume that the switching 30 device BE^1 has been operated, and that the corresponding code is being supplied to the line wires as explained above. I will also assume that during the delivery of this code, the switching device CE^1 is operated. The contact arm controlled by device CE^1 and corresponding to arm 20 operated by device BE^1 therefore becomes latched, but the apparatus is otherwise unaffected. At the conclusion of the code initiated by movement of device BE^1 , relay V^A becomes de- 40 energized as explained above, but since device CE^1 has been operated, relay L^A does not pick up. Instead, the circuit for code setting relay CW is closed, and the apparatus proceeds to operate the stepping contactor P^A and deliver the code corresponding to the setting determined by the relay CW . When the last code which has been stored in this manner has been delivered, relay L^A picks up and restores the apparatus to its normal condition as explained hereinbefore.

50 The purpose of the reset relay a is to permit the dispatcher to change a control code after the code transmission has been started, without requiring him to wait until the completion of the code already initiated. As explained hereinbefore, the reset relay a is energized in series with whichever one of the code-setting relays W happens to be energized. If the switching device corresponding to this code-setting relay is operated during the transmission of the corresponding 55 code, contact 19 associated therewith is opened, and the circuit is immediately interrupted for both the code-setting relay and the reset relay a . Thus, if switching device BE^1 has been operated, and the corresponding code is being delivered, the code-setting relay BW will be energized in series with reset relay a . If, now, switching device BE^1 is restored to its original position, contact 19 controlled thereby will be operated briefly during transit of the lever 12, thereby deenergizing relays BW and a . This causes the contacts on the code-setting relay to be opened, and further operation of the stepping contactor to its starting position can not cause operation of the transmitting relays to produce interruptions in the line circuits. The opening of relay 60

a , however, supplies current directly to the transmitting relay AT^3 over back contact 68 of relay a and front contact 67 of relay b . The energization of relay AT^3 holds relays AR^1 and AR^2 de-energized so that relay Q^A is also deenergized, 5 thereby insuring that relays K^A and H^A remain energized until the stepping contactor P^A has completed its cycle of operation and returned the spider 26 to engagement to the segment 27 for the proper location of the spider to begin the 10 new code.

Referring now to Fig. 2, the line relays BR^1 and BR^2 are normally included in the line circuit extending to the dispatcher's office and to each of the other remote stations. When a control code is transmitted, as explained above, the first interruption of line wires 1 and 2 (which, it will be remembered, was caused by the preliminary energization of transmitting relay AT^3 while contact 28-27 of stepping contactor P^A was 20 closed, prior to the beginning of the actual control code) de-energizes both relays BR^1 and BR^2 . These relays control relay Q^B in a manner similar to the control of relay Q^A by relays AR^1 and AR^2 at the dispatcher's office, and relay Q^B controls 25 two slow-release relays K^B and H^B which function in the same manner as the office relays K^A and H^A already described. The preliminary impulse just described therefore de-energizes relay Q^B . When this happens, current flows from 30 terminal B over back contact 100 of relay Q^B through relays K^B and H^B in parallel to terminal C, thereby energizing the two latter relays. At the conclusion of the preliminary impulse, relays BR^1 and BR^2 again become energized, and relay 35 Q^B again picks up. This preliminary operation of the relays at the remote station is utilized in checking and locking functions which will be referred to more specifically hereinafter and is not considered as a part of the code. In the 40 control code which was previously described, the first station selecting code element was produced by interrupting line wire 2 and it will be seen that this code element results in the de-energization of relay BR^2 without interfering with relay BR^1 . 45 In this connection, it should be pointed out that the corresponding line relays at each of the other remote stations operate in unison with the line relays at station B, and it is necessary to provide, at each station, apparatus which is selectively responsive to the character of the several code elements and to the sequence in which such code elements are received. Any suitable selecting apparatus may be utilized for this purpose, but for purpose of illustration, I have shown decoding relays, two of which are provided at 50 station B and designated by the reference characters BN^1 and BN^2 . Each of these decoding relays has a holding circuit and three stepping circuits which control a biased movable member 55 progressively away from an initial condition to close a contact 77 at the end of a predetermined number of steps, in this case six, but only if the stepping circuits are energized in a predetermined sequence corresponding to the code pattern to 60 which the decoding relay is adapted to respond and if the holding circuit is closed during the intervals between successive closings of the stepping circuits. The decoding relays furthermore function in such manner as to allow the movable member to return to its initial condition upon the reception of a selecting element which does not correspond to the particular pattern to which the relay is adapted to respond, so that only the decoding relay which has been operated through 65 70 75

five steps in response to the first five elements of the code will be conditioned to close its contact 11, the contact 11 of the selected relay becoming closed upon reception of the final element irrespective of the character of that element. One form of decoding relay which will operate in the manner described is disclosed and claimed in a co-pending application for Letters Patent of the United States, Serial No. 378,894, filed the 10 17th day of July, 1929, by Clarence S. Snavely for Remote controlling apparatus. As here shown, the two decoding relays BN1 and BN2 are connected in parallel, the holding circuits for these relays including front contacts on both line 15 relays BR1 and BR2. These holding circuits may be traced from terminal B, front contacts 69 and 71 of relay BR1, front contact 72 of relay BR2, wire 73, thence through the decoding relays BN1 and BN2 in parallel to wire 74 and over 20 a front contact 75 of relay HB, and back contact 76 of relay MB to terminal C. Wire 74 extending from the decoding relays over contacts 75 and 76 of relays HB and MB to terminal C, also serves as a common return for the 25 stepping circuits which are controlled over wires e, f, and h. Wire e is connected with terminal B over back contact 71 of relay BR1, front contact 70 of relay BR2 and back contact 69 of relay BR1 when relay BR1 is de-energized and relay BR2 30 is energized. When relay BR2 is deenergized and relay BR1 is energized, terminal B is connected with wire f over front contact 69 of relay BR1, front contact 71 of relay BR1 and back contact 72 of relay BR2. When relays BR1 and BR2 are 35 both de-energized, wire h is connected with terminal B over back contact 69 of relay BR1 and back contact 70 of relay BR2. Front contact 75 of relay HB included in the common return for the stepping and holding circuits for the decoding relays closes when relay HB becomes energized at the beginning of the code, and opens to allow the operated decoding relay to return to normal when relay HB releases at the end of the code. Back contact 76 of relay MB in the common 40 return is opened to prevent the operation of the decoding relays when an indication code is being transmitted from the station, as herein-after described.

The two decoding relays at station B are designed to close their contacts 11 selectively in response to control codes originating at panel B in the dispatcher's office. It will be remembered that the first four elements selecting of all control codes originating at panel B are the same, 55 and each of these codes will operate both relays BN1 and BN2 through four steps. If the switch lever of panel B is reversed, the fifth impulse is produced by opening line wire 2, and when this impulse is received, the decoding relay BN1 at station B advances one step and relay BN1 releases. If on the other hand, the switch lever of panel B is normal, the fifth element of the code is produced by opening line wire 1, and in that case, the decoding relay BN1 advances one 60 step and relay BN2 releases. When the last element of the control code previously described is received at station B, therefore, relay BN2 selectively closes its contact 11, and since relays BR1 and BR2 both become de-energized, terminal B is connected with wire h, and current flows from this wire through the left-hand winding of relay BY3, contact 11 of decoding relay BN2, and right-hand winding of relay BY1 to terminal C. Relay BY3 holds its contact 85—85b 65 open and relay BY1 reverses to close contact

78—78b. When this happens, a pick-up circuit is completed for relay p² over contact 37 operated by switch 7. Relay p² then becomes energized, and an operating circuit is completed for motor g, from terminal B, over front contact 5 79 of track relay v, front contact 80 of relay p², armature 10 of motor g, front contact 81 of relay p², and field 11 of motor g to terminal C. When this circuit is closed, motor g operates to drive the switch 7 towards its reverse position. 10 When the switch attains its full reverse position, contact 37 opens, thereby de-energizing the relays p². Of course relay BY1 is energized for only a brief interval of time during the last element of the control code, but the contacts of this 15 relay remain in the position to which they were last moved.

If the dispatcher wishes to restore switch 7 to its normal position, he returns the switch lever of panel B to the normal position in which it is 20 illustrated in the drawings. This operation results in the transmission, in a manner which will be readily understood from the preceding description, of a control code, similar in all respects to the code previously described, except 25 that since contact 14—16 of switching device BE1 is now closed, the fifth element of the code now transmitted will be produced by opening line wire 1 instead of line wire 2. When this code is received at station B, the decoding relay BN1 30 selectively closes its contact 11 while relay BN2 releases. When the final impulse of the code is received, relays BR1 and BR2 are both de-energized as before, and current flows through the left-hand winding of relay BY3 as previously 35 explained, and thence through contact 11 of relay BN1 and the left-hand winding of relay BY1 to terminal C. Contact 78—78a is therefore closed and an operating circuit is completed for switch relay p¹ over contact 36 controlled by 40 switch 7. Relay p¹ therefore picks up, and completes an operating circuit for motor g, from terminal B, over front contact 82 of track relay v, front contact 83 of switch relay p¹, armature 10 of motor g, front contact 84 of relay p¹, and 45 field 11 of motor g, to terminal C. When this circuit is closed, the motor g operates to drive switch 7 towards its normal position, and when the switch has attained its full normal position, the opening of contact 36 de-energizes relay p¹ 50 to stop the motor g.

It will be remembered that the character of the last element of each code is determined by the position of the signal lever of the switching device BE2 or of the corresponding switching device of any other panel at which the code originates. When the signal lever occupies its normal position as shown this final element of the code is produced by opening both the line circuits 55 so that relays BR1 and BR2 both become de-energized, the left-hand winding of relay BY3 is energized as described hereinbefore so that contact 85—85b of relay BY3 is open and all signals at station B indicate stop. If a dispatcher wishes 60 to clear an eastbound signal at station B, he may do so by moving the signal lever of the switching device BE2 to its left-hand position in which contact 14—15 is closed, so that the final element of the code then transmitted is produced 65 by opening line wire 1. When this code is received at station B, relay BR1 is de-energized during the final code element, and current flows from terminal B to wire e and thence through 70 the left-hand winding of relay BY2 and the right- 75

hand winding of relay BY3 and thence through the contact of one or the other of relays BN¹ or BN², depending upon the position of the switching device BE¹ on panel B at the dispatcher's office, and the corresponding winding of relay BY1 to terminal C. When this happens, contact 83—86^a of relay BY2 is closed, if this contact is not already closed, and contact 85—85^b of relay BY3 is also closed. A circuit is then completed for signal relay q¹, current flowing from terminal B, over contact 85—85^b of relay BY3, contact 86—86^a of relay BY2, and winding of relay q¹ to terminal C. Assuming that the switch 7 occupies its normal position, so that the relay k is energized to swing its polar contacts to the left, the energization of relay q¹ completes a circuit for signal w² from terminal B, over front contact 87 of track relay v, front contact 88 of relay q¹, front contact 89 of relay k, normal contact 90 of relay k, and the operating mechanism of signal w² to terminal C.

Of course, if the switch lever is reversed and the signal lever is moved to the left the fifth element of the code is produced by interrupting line wire 2 so that the switch 7 at station B is moved to its reverse position, and the final element of the code is produced by interrupting line wire 1 so that signal relay q¹ becomes energized as described above, but in this case the operating circuit for signal w¹ is completed from terminal B over front contact 87 of track relay v, front contact 88 of relay q¹, front contact 89 of relay k, reverse contact 90 of relay k and operating mechanism of signal w¹ to terminal C.

If, however, the switch lever of the switching device BE¹ occupies the normal position in which it is illustrated on Fig. 1, and the signal lever of the switching device BE² is operated to the right to close contact 14—17, the control code then delivered to station B has its fifth element formed by interrupting line wire 1 and has its sixth element formed by opening line wire 2, and at station B a circuit is closed during the sixth element of this code from terminal B to wire f and thence through the right-hand winding of relay BY2 and the right-hand winding of relay BY3, contact 71 of relay BN¹, and the left hand winding of relay BY1 to terminal C.

Current then flows from terminal B over contact 85—85^b of relay BY3, contact 86—86^a of relay BY2, and winding of relay q² to terminal C. Relay q² therefore becomes energized and current flows from terminal B over front contact 87 of track relay v, front contact 91 of relay q², front contact 92 of relay k, normal contact 93 of relay k, and operating mechanism of signal w⁴ to terminal C. If, however, the switch 7 occupies its reverse position when signal relay q² is energized, relay k would occupy a position in which its polar contacts were swung to the right and an operating circuit would then be closed for signal w³, from terminal B, over front contact 87 of track relay v, front contact 91 of relay q², front contact 92 of relay k, reverse contact 93 of relay k, and operating mechanism of signal w³ to terminal C.

All signals can be restored to the stop position by restoring the signal lever of the switching device BE² to the normal position in which it is shown in the drawings. If this is done, the sixth element of the control code delivered to station B is produced by opening both wires 1 and 2 so that relays BR¹ and BR² both open, and during this sixth element of the code, current is supplied

to the left-hand winding of relay BY3 thereby opening contact 85—85^b of this relay and de-energizing both signal relays q¹ and q², as explained above in connection with the operation of the switch.

It should be pointed out that with the apparatus thus far described, I have provided apparatus which controls both the switch and signals at a remote station, in accordance with the position of the control levers on the corresponding panel at the dispatcher's office with a single code. That is to say, only one control code is required to position all apparatus at one station, in accordance with the positions then occupied by the control levers on the corresponding panel in the dispatcher's office.

In order to inform the dispatcher concerning the condition of apparatus at the several remote stations, each remote station is provided with apparatus for delivering to the line circuits, indication codes for operating the line relays at the dispatcher's office in accordance with the condition of the apparatus at the remote station. Referring particularly to the apparatus located at station B, Fig. 2 illustrates indication code transmitting apparatus which includes a plurality of delivery units, here shown as three in number and designated by the reference characters G¹, G² and G³. Each of these delivery units is similar to the coding units disclosed and claimed in an application for Letters Patent of the United States, Serial No. 254,684, filed by Clarence S. Snavely on Feb. 16, 1928, for Railway traffic controlling apparatus. Each of the delivery units G comprises a storing magnet r having an armature which is biased to the right by a spring contact 97. When the storing magnet is energized, the armature is moved to its left hand or attracted position, thereby closing front contact 91, and a latch 141 then drops into a position in which the armature is mechanically held in its attracted position. Each delivery unit also comprises a delivery magnet d provided with an armature which operates a trigger 142. If a storing magnet r is energized and the associated delivery magnet d is then energized, the trigger 142 is moved to the left, thereby lifting the latch 141 of the storing magnet and releasing the armature of the storing magnet. It should be observed, however, that when the trigger 142 is held in its left-hand position by energization of the magnet d, the armature of the storing magnet r is held in its left or attracted position, even though the storing magnet may be electrically de-energized.

In addition to the delivery units G, the indication code transmission equipment at each remote station comprises a stepping contactor and stepping magnet designated by the reference characters P and F with distinguishing exponents, and a group of relays associated therewith and similar in function to the relays L^A, K^A, M^A, V^A, H^A, D^A and J^A, at the dispatcher's office.

In explaining the operation of the equipment during the transmission of an indication code, I will first assume that switch 7 at station B is being moved to its reverse position. Relay p² is energized during this movement of the switch, and when the switch attains its full reverse position, contact 94—94^b becomes closed and current flows from terminal B over contact 94—94^b, front contact 117 of relay p², through the right-hand winding of relay i¹ and winding of storing magnet r of delivery unit G² to terminal C. Of course relay p² becomes de-energized when the

switch attains its reverse position, and the circuit just traced is closed for only a brief interval of time, but during this brief interval the armature of the storing magnet r of unit G^2 is attracted 5 and latched, and contact 96—96^b of relay i^2 becomes closed.

Relay L^B is normally held energized over a circuit which may be traced from terminal B through back contact 98 of relay V^B , contact 10 44—44^a of relay J^B , resistor 99, thence through the back contact 97 of the storing magnets r of all of the delivery units G in series, and the winding of relay L^B to terminal C. When the storing magnet r of unit G^2 is energized, as described above, the circuit just traced for relay 15 L^B is interrupted, so that the back contact 103 of this relay becomes closed. This operation completes a pick-up circuit for relay BS which may be traced from terminal B, over front contact 20 100 of relay Q^B , back contact 101 of relay K^B , winding of relay BS , and back contact 103 of relay L^B , to terminal C. Relay BS now becomes energized, and the opening of back contacts 104 and 105 of this relay opens the line 25 wires 1 and 2 to all stations more remote from the dispatcher's office than station B. Furthermore, the closing of front contacts 104 and 105 connects the line wires 1 and 2 to the dispatcher's office through the line relays BR^1 and 30 BR^2 , respectively, and through back contacts on the transmitting relays BT^1 , BT^2 and BT^3 , with the common return wire 3. Relays BR^1 and BR^2 therefore remain energized if the line 35 is clear between station B and the dispatcher's office. When relay BS becomes energized, however, a circuit is completed for relay BT^3 , from terminal B, over front contact 100 of relay Q^B , back contact 101 of relay K^B , back contact 107 of magnet F^B , contact 26—27 of stepping contactor P^B , winding of relay BT^3 , and front contact 143 of relay BS , to terminal C. Relay BT^3 then becomes energized and interrupts line wires 40 1 and 2 to the dispatcher's office at back contacts 103 and 109, respectively. This operation de-energizes relays BR^1 and BR^2 and also de-energizes all line relays at the dispatcher's office and at all remote stations between station B and the dispatcher's office. At station 45 B, relay Q^B is de-energized, and the closing of back contact 100 of this relay closes the circuits for relays H^B and K^B , whereupon these relays become energized. When relay K^B becomes energized, the circuits previously traced for relays BS and BT^3 are opened, so that these 50 relays become de-energized. Relay BS , however, is slow-releasing and holds its front contact closed until current is again supplied to this relay, as will be described hereinafter. Relay BT^3 , however, releases, thereby restoring the line circuits 1 and 2 to the dispatcher's office. Relays BR^1 and BR^2 then become energized, and hence pick up relay Q^B , whereupon a circuit is closed for relay M^B from terminal B, over front contact 100 of relay Q^B , front contact 101 of relay K^B , winding of relay M^B , front contact 144 of relay BS , and back contact 103 of relay L^B , to terminal C. The circuit just traced is provided with a branch which passes from one terminal of relay M^B through back 55 contact 110 of relay V^B , back contact 111 of relay D^B , winding of magnet F^B and thence as before, over front contact 144 of relay BS and back contact 103 of relay L^B to terminal C. When the circuit and its branch just described 60 are closed, relay M^B and magnet F^B become en-

ergized. When magnet F^B picks up, its back contact 107 opens, and its front contact closes, thereby breaking the circuit to the spider 26 of stepping contactor P^B , and energizing relay D^B over a circuit which may be traced from terminal B, through front contact 112 of relay M^B , front contact 107 of magnet F^B , and winding of relay D^B to terminal C. Magnet F^B and relay D^B thereafter operate to advance stepping contactor P^B in a manner which will be apparent 10 from the previous description of the operation of the stepping contactor P^A at the dispatcher's office. It will be observed that, as shown in the drawings, the spider 26 of contactor P^B rotates in a counter-clockwise direction. 15

When relay M^B became energized, it completed a stick circuit over its own front contact 113 and also restored energy to relay BS over a circuit which includes front contact 112 of relay M^B and back contact 103 of relay L^B . Furthermore, the closing of front contact 76 of relay M^B completes the circuit for the delivery magnet d of unit G^2 . This circuit may be traced from terminal B over back contact 98 of relay V^B , contact 44—44^a of relay J^B , resistor 99, back contact 97 of storing magnet r of unit G^1 , front contact 97 of storing magnet r of unit G^2 , winding of delivery magnet d of unit G^2 , and front contact 76 of relay M^B to terminal C. The delivery magnet d of unit G^2 then becomes energized and moves trigger 142 into engagement with the armature of storing magnet r . This operation releases the latch 141 but holds front contact 97 of the storing magnet closed until the delivery magnet d subsequently 35 becomes de-energized. When the delivery magnet d closes its front contacts, the right-hand winding of master relay J^B is connected across the resistor 99 over a circuit which may be traced from one terminal of the resistor through 40 contact 44—44^a of relay J^B , the right-hand winding of relay J^B , front contact 114 of delivery magnet d , front contact 97 of the storing magnet r of unit G^2 , and back contact 97 of storing magnet r of unit G^1 , back to the other terminal 45 of the resistor 99. The potential drop across resistor 99 due to current flowing through this resistor to the delivery magnet d is sufficient to energize the relay J^B , which then swings its contact to the right to close contact 44—44^b. 50

The operation of the stepping contactor P^B , described above, connects spider 26 successively with segments 28, 29, 30 and 31 and energizes selected ones of the transmitting relays BT^1 , BT^2 , and BT^3 in a predetermined sequence to 55 produce the first four elements of an indication code. These first four elements are utilized to select, at the dispatcher's office, a particular control panel corresponding to the station at which the indication code originates and for 60 convenience I prefer to utilize, for indication codes from a particular station, the same sequence of code elements that is used in the control codes for operating apparatus at such remote station; however, this particular arrangement is not essential but only desirable because of the resulting economy in the total number of codes necessary to control a given number of stations. The decoding relays BN^1 and BN^2 however do not respond when indication codes 70 are transmitted from the same station, because relay M^B is then energized and the common return wire 74 is open at back contact 76.

The first four elements of all indication codes originating at station B are the same, but when 75

the spider 26 engages segment 32 to produce the fifth element of the code now being described, a circuit is completed, from terminal B, over front contact 112 of relay M^B, back contact 107 of relay F^B, contact 26—32 of stepping contactor P^B, front contact 115 of delivery magnet d of unit G², and winding of relay BT2, to terminal C. The fifth element of the code is therefore produced by opening line wire 2. In similar manner the sixth element of the code is produced by opening line wire 2, the circuit for relay BT2 during the sixth element of the code passing from terminal B, over front contact 112 of relay M^B, back contact 107 of relay F^B, contact 26—33 of contactor P^B, front contact 116 of delivery magnet d of unit G², contact 95—96^b of relay i¹ (which, it will be remembered was closed as a result of the reversal of switch 7), and winding of relay BT2 to terminal C. In similar manner, the fifth and sixth elements of each indication code are determined by the delivery magnets d of the units G in conjunction with the relays i¹ and i².

After the completion of an indication code, the stepping contactor P^B moves the spider 26 into engagement with segment 34. When this happens, relay V^B is energized over a circuit which is obvious from the drawings, and the circuit is then interrupted for the delivery magnet d of unit G², which releases its armature and permits trigger 142 to release the armature of storing magnet r. Furthermore, a circuit is completed over front contact 98 of relay V^B for the left hand winding of master relay J^B, so that contact 44—44^a of this relay becomes closed. The energization of relay V^B also interrupts the circuit for relay F^B, and spider 26 of stepping contactor P^B pauses in engagement with segment 34. When the contactor is in this position, however, the line circuits are closed so that relays BR1, BR2 and Q^B are energized. Relays H^B and K^B are therefore de-energized, and after the expiration of a brief interval of time, relay H^B releases. When this happens, current is again supplied to relay F^B from terminal B over front contact 113 of relay M^B, back contact 145 of relay H^B, back contact 111 of relay D^B, winding of relay F^B, front contact 144 of relay BS and back contact 103 of relay L^B. The energization of relay F^B interrupts the circuit previously traced for relay V^B and allows the latter relay to release in case there is no storing magnet r energized. The de-energization of relay V^B completes the circuit for the starting relay L^B, and when this relay picks up, it breaks the circuit for relays BS and M^B and these relays both become de-energized. When relay M^B opens its front contacts, relay F^B becomes de-energized and since the remaining relays at station B are now de-energized, it follows that the apparatus is restored to its normal position. It should be noted that the final de-energization of relay F^B restores the spider 26 of stepping contactor P^B to engagement with segment 27 so that the apparatus is left in condition for delivery of a new code.

It should also be pointed out that when relay BS becomes de-energized, the line circuits are re-established to all stations beyond station B.

For the purpose of indicating the character of the indication codes received at the dispatcher's office, the line relays AR1 and AR2 control decoding relays Bn1 and Bn2 similar in all respects to the decoding relays BN1 and BN2 described in connection with the apparatus located at station B. Each panel at the dispatcher's office will

be provided with decoding relays n which will be arranged to close their contacts 77 only in response to indication codes originating at the station corresponding to such panel. For example, relay Bn1 on panel B closes its contact 77 only when an indication code originating at station B has its fifth element produced by opening line wire 1 and decoding relay Bn2 is arranged to close its contact 77 only if the indication code received from station B has its fifth element produced by opening line wire 2. The wires e, f, and h control the stepping circuits of the decoding relays n in accordance with the character and sequence of the received indication code elements in the same manner as described in connection with the apparatus at station B. Thus, when a coding element is produced by opening line wire 1 terminal B is connected with wire e, when a code element is produced by opening line wire 2, terminal B is connected with line wire f and when the code element is produced by opening both line elements 1 and 2, terminal B is connected with wire h.

When the indication code previously described is received from station B as a result of the movement of the switch 7 to its reverse position, relay Bn2 becomes selectively energized. When the sixth element of the code is received, terminal B is connected with wire f, and current flows from this wire through the right hand winding of relay By1 and contact 77 of decoding relay Bn2 to terminal C. Contact 120—120^b of relay By1 therefore becomes energized and current is supplied over this contact to a lamp 121, thereby informing the dispatcher that switch 7 at station B occupies its reverse position.

If the switch is restored to its normal position at station B, a circuit is completed for a brief interval over contact 94—94^a operated by the switch, and front contact 95 of switch relay n¹ through the left hand winding of relay i¹ and the storing magnet r of unit G². This operation initiates the delivery of an indication code from station B, the apparatus functioning as described hereinbefore, with the exception that the final element of the indication code now delivered to the line circuit is produced by energizing transmitting relay BT1 to open line wire 1. In all other respects, the operation is identical to the transmission of the code previously described so that the reception of this indication code at the dispatcher's office picks up the decoding relay Bn2 during the fifth element of the code and when the sixth element of the code is received, terminal B is connected with wire e and current flows from this wire through the left hand winding of relay By1 and contact 77 of relay Bn2 to terminal C. Contact 120—120^a of relay By1 is therefore closed, and current is supplied to lamp 122 to indicate to the dispatcher that the switch 7 at station B occupies its normal position.

The apparatus is also arranged to inform the dispatcher concerning the condition of the signals at station B. The signal indication is controlled by delivery unit G³, which is in turn controlled by circuit controllers on the signals and by the signal relays q¹ and q². For example, I will assume that signal w² is moved to the proceed position. Contact 129 controlled by signal w² is arranged to close for a brief interval just before the signal attains its proceed position. At this time relay q¹ is energized, and a circuit is then completed from terminal B, over front contact 127 of relay q¹ and contact 129 controlled by signal w² through the right hand winding of relay 75.

i^2 and storing magnet r of unit G^3 to terminal C. The circuit just traced is provided with a branch around contact 129 including a similar contact 131 operated by signal w^1 just before this signal reaches its proceed position. Another branch for the circuit just traced, may be traced from terminal B over front contact 132 of relay q^2 and contact 133 operated by signal w^4 . Still another branch for this circuit may be traced from terminal B over front contact 132 of relay q^2 and contact 134 operated by signal w^3 and thence as before to the right hand winding of relay i^2 . It follows therefore, that when any signal moves to the proceed position, a circuit is closed which energizes the storing magnet r of unit G^3 and closes contact 130—130^b of relay i^2 . The apparatus at station B then operates to deliver an indication code to the dispatcher's office and the parts are so arranged that the fifth element of this indication code is produced by opening line wire 1, thereby selectively energizing the decoding relay Bn^1 at the office. The sixth element of this indication code is produced by energizing relay BT^3 so that both line wires to the dispatcher's office are opened and as a result, terminal B is connected with wire h at the dispatcher's office during the final element of the indication code. During this final element of the code, current flows from wire h through the right hand winding of relay By^2 and contact 77 of relay Bn^1 to terminal C. Contact 119—119^b of relay By^2 is therefore closed, and current is supplied over this contact to lamp 139 to indicate to the dispatcher that a signal at station B occupies the proceed position.

The indication of the return of a signal to its stop position is similar to the indication of the proceed position, and is accomplished by contacts 135, 136, 137 and 138 controlled by signals w^2 , w^1 , w^4 and w^3 , respectively, in such manner that each contact is closed for a brief interval during movement of the corresponding signal from its proceed to its stop position just prior to the instant that the signal attains its full stop position. When any signal returns to its stop position, a circuit is completed for the left hand winding of relay i^2 and the storing magnet r of unit G^3 . It is unnecessary to trace all of these circuits in detail and for purposes of illustration, I will assume that signal w^2 returns to its stop position. Current then flows from terminal B, over back contact 127 of relay q^1 , contact 135 operated by signal w^2 , left hand winding of relay i^2 and winding of storing magnet r of delivery unit G^3 , to terminal C. The energization of storing magnet r initiates the transmission of an indication code from station B, and since this indication code has its fifth element produced by opening line wire 1, the decoding relay Bn^1 on panel B at the dispatcher's office becomes selectively energized. During the sixth element of the code, however, relay BT^2 is energized over contact 130—130^a of relay i^2 , so that line wire 2 is opened to produce the last element of the code and as a result, at the dispatcher's office, terminal B is connected with wire f and current flows from this wire through the left hand winding of relay By^2 and contact 77 of relay Bn^1 to terminal C. Contact 119—119^a of relay By^2 is then closed to light lamp 140 and thereby indicate to the dispatcher that a signal at station B has moved to the stop position.

In addition to information concerning the position of the devices at a station which are controlled by the dispatcher from his office, it is sometimes desirable to give him information con-

cerning traffic conditions adjacent this device. For example, it might be desirable for the dispatcher to know when a train leaves the track section 5—6 at station B. For this purpose, I provide a repeater relay z controlled by front contact 125 of track relay v . Relay z is therefore normally energized when the section 5—6 is unoccupied but is de-energized when the section is occupied. The relay z is somewhat slow-acting so that when a train leaves section 5—6, thereby allowing relay v to become energized, a brief interval of time elapses before relay z opens its back contacts. During this brief interval of time a circuit is completed for the storing magnet r of delivery unit G^1 . This circuit may be traced from terminal B, over front contact 123 of relay v and back contact 126 of relay z , through winding of storing magnet r to terminal C. When the storing magnet r becomes energized, the apparatus operates to deliver an indication code to the line circuits, and it will be seen from the drawings that the fifth element of this indication code is produced by energizing relay BT^1 so that line wire 1 is opened and decoding relay Bn^1 at the dispatcher's office becomes selectively energized. The sixth element of the indication code is also produced by energizing relay BT^1 , so that during this sixth element of the code, the wire e at the dispatcher's office is connected with terminal B, and current flows from this wire through magnet 126 of a graphic train recorder and contact 77 of relay Bn^1 to terminal C. The magnet 126 is shown only by way of example and might be replaced by any other suitable indicating device. The operation of this magnet therefore indicates to the dispatcher the fact that a train has left section 5—6 at station B.

It is, of course, understood that the lamps 121, 122, 139 and 140 at the dispatcher's office are associated with panel B and would ordinarily be located on the control panel adjacent the levers which operate the switching devices BE^1 and BE^2 which have been illustrated apart from this panel for purposes of simplicity.

Attention should also be drawn particularly to the fact that the apparatus at the dispatcher's office and at each remote station including the sectionalizing relays AS , BS , etc., and the relays K , M , H , etc., operate to provide checking and locking functions which prevent the transmission of code to the line circuits from any station when another station is transmitting a code. These checking and locking operations are described in detail in the Snavely application, Serial No. 362,948 identified above.

It will be plain from the foregoing that I have herein shown and described a code system of communication, control, and indication, in which a plurality of direct wire line circuits are separately controlled to give distinctive code elements. By combining these code elements in different sequences, I build up different codes for transmitting different control and indication functions. The selection between these different codes may be accomplished in any suitable manner and I do not wish to be limited in any respect to the use of the particular decoding relays which I have illustrated only for purposes of explanation. The only requirement is that some apparatus be utilized which will respond selectively to the sequence in which code elements of different characters are received.

Although I have herein shown and described only one form of remote controlling apparatus embodying my invention, it is understood that

various changes and modifications may be made therein within the scope of the appended claims without departing from the spirit and scope of my invention.

Having thus described my invention, what I claim is:

1. A centralized traffic controlling system for railroads comprising a control office and a station located at spaced points, line wires extending between said two points and affording a plurality of channels of communication between such points, means at each point for creating a series of distinctive code elements by modifying the electrical conditions of said channels individually or in combination, and means at each point selectively responsive to a series of such code elements originating at the other point.

2. A centralized traffic controlling system for railroads comprising a control office and a station located at spaced points, line wires extending between said two points and affording a plurality of channels of communication between such points, means at each point for creating a series of distinctive code elements by modifying the electrical conditions of said channels separately or in combination, a plurality of circuits at each point each arranged to be closed when an individual one of said code elements is delivered to said channel at the other point, and means at each point selectively controlled in accordance with the sequence in which the associated circuits are closed.

3. A centralized traffic controlling system for railroads comprising a control office and a station located at spaced points, a plurality of line circuits extending between said two points, a plurality of relays at each point each arranged when operated to deliver a code element to a different one or combination of said line circuits, means for operating selected ones of said relays in a predetermined sequence, and means at each point selectively responsive to the sequence in which code elements are delivered to said line circuit or combinations of line circuits at the other point.

4. In combination, two line circuits extending between two spaced points, and each including a line relay at one said point, a first and a second transmitting relay at the other point each arranged when operated to control an individual one of said line circuits, a third transmitting relay arranged when operated to control both said line circuits, means for operating selected ones of said transmitting relays in a selected sequence, and means selectively responsive to the sequence of operation of said line relays.

5. In combination, two line circuits extending between two spaced points, and each including a line relay at one said point, a first and a second transmitting relay at the other point each arranged when operated to control an individual one of said line circuits, a third transmitting relay arranged when operated to control both said line circuits, means for operating selected ones of said transmitting relays in a selected sequence, a first circuit arranged to be closed when one said line relay is operated, a second circuit arranged to be closed when the other line relay is operated, a third circuit arranged to be closed when both line relays are operated, and means at said other point selectively controlled by said three circuits and arranged to respond only when selected ones of said circuits are closed in a predetermined sequence.

6. In combination, a plurality of line circuits,

a plurality of transmitting relays each arranged when operated to deliver a code element to a different one or combination of said line circuits, means for operating selected ones of said transmitting relays in a predetermined sequence to produce a complete code, a plurality of receiving devices, one for each line circuit and each arranged to be operated in response to control of the corresponding line circuit by a transmitting relay, and means selectively responsive to the sequence of operation of said receiving devices.

7. In combination a plurality of normally closed line circuits each including a source of energy and an individual line relay, a plurality of transmitting relays each arranged when operated to open a different one or combination of said line circuits, means for operating selected ones of said transmitting relays in a predetermined sequence, and means selectively responsive to the sequence of operation of said line relays.

8. In combination with a plurality of normally closed line circuits each including an individual line relay, manually controlled means for briefly interrupting said line circuits singly or in combination in a predetermined sequence to produce a code, a traffic governing device, and means selectively responsive to the sequence of operation of said line relays and actuated by said code to control said device.

9. In combination with a plurality of stations, a plurality of devices at each said stations, a plurality of normally closed line circuits connecting all said stations, means for producing control codes made up of code elements each formed by briefly opening a different one or combination of said line circuits, means at each station responsive to the sequence of a portion of the code elements of each code to select a station and means controlled by the remaining elements of each code to operate a selected device at said selected station.

10. In combination with a plurality of normally closed line circuits, a plurality of movable devices, a stepping contactor having a series of contacts and arranged to close the contacts of said series in order when the contactor is actuated, means set into operation by a change in the condition of any said device to actuate said stepping contactor, means operating when any contact of said series is closed to interrupt said line circuits singly or in combination according to the condition of the device which has been operated, means controlled by the last contact of said series for stopping said stepping contactor, and means selectively responsive to the sequence in which said line circuits are opened.

11. A remote control system of the code type comprising a plurality of line circuits extending between two points, a plurality of movable devices at one point, means responsive to a movement of any device for selectively interrupting said circuits singly or in combination to produce code elements in a sequence of which part is determined by the particular device operated and another part by the position into which such device is moved, and means at the other point selectively responsive to the entire sequence of such code elements.

12. A remote control system of the code type comprising a plurality of groups of movable devices, a plurality of line circuits, means responsive to the operation of any device for selectively controlling said circuits singly or in combination to produce code elements in a sequence of which one

- part is determined in accordance with the group containing the operated device and another part is determined by the position to which such device was moved, a plurality of groups of registering mechanisms, means controlled by said line circuits for selecting a particular group of said mechanisms in response to said one part of a sequence of code elements, and means for actuating a particular mechanism in the selected 10 group in accordance with said other part of such sequence.
18. In a centralized traffic controlling system for railroads, a control office and a station located at spaced points, a plurality of line circuits connecting said office and station, a plurality of movable levers at the office, means responsive to an operation of any lever for selectively controlling said circuits singly or in combination to produce a series of code elements of which one 15 part is determined in accordance with the lever which was moved and another part is determined by the position to which such lever was moved, selecting means at the station responsive selectively to said one part of a sequence of code 20 elements, and registering means at the station controlled by said selecting means and selectively responsive to said other part of said sequence.
19. In a centralized traffic controlling system for railroads, a control office and a plurality of stations, a plurality of line circuits extending from said office to said stations, a plurality of movable levers at the office, means responsive to an operation of any lever for selectively controlling said circuits singly or in combination to produce a series of code elements of which one part is determined in accordance with the lever which 25 was moved and another part is determined by the position to which such lever was moved, selecting means at each station responsive selectively to said one part of a particular sequence of code elements, and registering means at each station controlled by the associated selecting means and selectively responsive to said other part of a sequence.
20. Apparatus for communicating between two spaced points comprising means for establishing a plurality of communication channels between such points, means at one point for repeatedly controlling said channels to create a series of distinctive code elements during each of which one or another of said channels is controlled singly or a plurality of said channels is controlled in combination, a plurality of receiving relays at the other point operating selectively in response to the character of each said code element, and means controlled progressively by successive operations of said receiving relays and selectively responsive to the condition of such relays during each code element.
21. Apparatus for communicating between two points and comprising a plurality of line circuits extending between such points, means at one point for briefly interrupting said line circuits singly or in combination to produce a series of code elements in selected sequence, a plurality of normally energized line relays one included in each said line circuit and all located at the other said point, means for energizing all of said line relays during each interval between successive code elements, and means controlled progressively by said code elements and selectively responsive to the particular one or combination of said line relays deenergized during each code element.
22. In combination with a plurality of line circuits, a plurality of transmitting relays having back contacts each included in a different one or combination of said line circuits, and means for briefly energizing said transmitting relays selectively to periodically open said line circuits in a predetermined sequence.
23. In combination with a plurality of line circuits, a plurality of transmitting relays having back contacts each included in a different one
- 5 10 15 20 25 30 35 40 45 50 55 60 65 70 75 80 85 90 95 100
- part is determined in accordance with the group containing the operated device and another part is determined by the position to which such device was moved, a plurality of groups of registering mechanisms, means controlled by said line circuits for selecting a particular group of said mechanisms in response to said one part of a sequence of code elements, and means for actuating a particular mechanism in the selected 10 group in accordance with said other part of such sequence.
18. In a centralized traffic controlling system for railroads, a control office and a station located at spaced points, a plurality of line circuits connecting said office and station, a plurality of movable levers at the office, means responsive to an operation of any lever for selectively controlling said circuits singly or in combination to produce a series of code elements of which one 15 part is determined in accordance with the lever which was moved and another part is determined by the position to which such lever was moved, selecting means at the station responsive selectively to said one part of a sequence of code 20 elements, and registering means at the station controlled by said selecting means and selectively responsive to said other part of said sequence.
19. In a remote control system of the code type comprising line wires forming a plurality of 25 communication channels selectively controlled singly or in combination in different sequences to produce code elements in different patterns, receiving means comprising a selector normally in one condition, and means controlled by said 30 code elements for advancing said selector progressively away from said one condition in response to a particular code pattern, but for allowing said selector to return to said one condition upon the reception of a code element not 35 corresponding to said particular pattern.
20. Apparatus for communicating between two spaced points comprising means for establishing a plurality of communication channels between such points, means at one point for repeatedly 40 controlling said channels to create a series of distinctive code elements during each of which one or another of said channels is controlled singly or a plurality of said channels is controlled in combination, a plurality of receiving relays at 45 the other point operating selectively in response to the character of each said code element, and means controlled progressively by successive operations of said receiving relays and selectively responsive to the condition of such relays during 50 each code element.
21. Apparatus for communicating between two points and comprising a plurality of line circuits extending between such points, means at one point for briefly interrupting said line circuits singly or in combination to produce a series of code elements in selected sequence, a plurality of normally energized line relays one included in each said line circuit and all located at the other said point, means for energizing all of said line relays during each interval between successive code elements, and means controlled progressively by said code elements and selectively responsive to the particular one or combination of said line relays deenergized during each code element.
22. In combination with a plurality of line circuits, a plurality of transmitting relays having back contacts each included in a different one or combination of said line circuits, and means for briefly energizing said transmitting relays selectively to periodically open said line circuits in a predetermined sequence.
23. In combination with a plurality of line circuits, a plurality of transmitting relays having back contacts each included in a different one
- 5 10 15 20 25 30 35 40 45 50 55 60 65 70 75 80 85 90 95 100

- or combination of said line circuits, a series of contacts, means for operating the contacts of said series in succession, and means effective when any contact of said series is closed to briefly energize a selected one of said transmitting relays to open the corresponding line circuits. 5
24. In a remote control system of the code type, a plurality of line circuits, a plurality of transmitting relays each arranged when energized to open a different one or combination of said line circuits, a movable device, stepping mechanism, means responsive to a movement of said device to actuate said stepping mechanism, and means controlled by said stepping mechanism for briefly energizing selected ones of said transmitting relays in a predetermined sequence which depends upon the position of said device. 10
25. In a remote control system of the code type, a plurality of line circuits, a plurality of transmitting relays each arranged when energized to open a different one or combination of said line circuits, a movable device, stepping mechanism, means responsive to a movement of said device to initiate operation of said stepping mechanism, other means for subsequently continuing the operation of said stepping mechanism through a complete cycle, and means controlled by said stepping mechanism for briefly energizing selected ones of said transmitting relays in a predetermined sequence which depends upon the position of said device. 15
26. In a remote control system of the code type, a plurality of line circuits, a plurality of transmitting relays each arranged when energized to open a different one or combination of said line circuits, a plurality of movable devices, stepping mechanism, means responsive to a movement of any device to actuate said stepping mechanism, and means controlled by said stepping mechanism for briefly energizing selected ones of said transmitting relays in a predetermined sequence one part of which is determined by the device which was moved and another part of which is determined by the position occupied by the device after such movement. 20
27. Transmitting apparatus for a remote controlling system of the code type comprising a plurality of normally closed line circuits, a plurality of transmitting relays each effective when energized to open a different one or combination of said line circuits, and means for selectively energizing said transmitting relays for brief intervals in a definite sequence. 25
28. In combination with a plurality of normally closed line circuits, a plurality of stations each comprising a transmitter for selectively interrupting said line circuits in predetermined sequences, a slow releasing relay at each station for preventing initiation of the operation of the corresponding transmitter when the relay armature is in attracted position, a quick releasing relay included in each line circuit at each station, and means effective when any quick releasing relay is deenergized to energize the associated slow releasing relay. 30
29. In combination with a plurality of normally closed line circuits, a plurality of stations each comprising a transmitter for selectively interrupting said line circuits in predetermined sequences to form a signal, a slow releasing relay at each station for preventing the initiation of the operation of the corresponding transmitter when the relay armature is in attracted position, the time required for said relay to release being greater than the interval between successive interruptions in said signal, a quick releasing relay included in each line circuit at each station, and means effective when any quick releasing relay is deenergized to energize the associated slow releasing relay. 5
30. In combination with a plurality of circuits controlled selectively in a predetermined sequence, a plurality of line relays one in each said line circuit, receiving means selectively responsive to the sequence of operation of said line relays, means responsive to a first operation of any said line relay for placing said receiving means under the control of said line relays, and means effective upon the cessation of operation of said line relays for removing said receiving means from the control of said line relays. 10
31. In combination with a plurality of normally closed line circuits selectively interrupted in a predetermined sequence, a plurality of line relays one included in each said line circuit, receiving means selectively responsive to the sequence in which said line relays are deenergized, means responsive to the first operation of any said line relay to place the receiving means under the control of said line relays, and means effective when said line relays are all steadily energized to remove the receiving means from control by said line relays. 15
32. In combination with a plurality of circuits controlled selectively in a predetermined sequence, a plurality of line relays one in each said line circuit, a normally open contact, means for closing said contact upon the first operation of any line relay and for reopening said contact upon the cessation of operation of the line relays, and receiving means selectively responsive to the sequence of operation of said line relays provided only said contact is closed. 20
33. In a remote control system comprising a plurality of normally closed line circuits each including a line relay, means for selectively opening said line circuits in a predetermined sequence to produce a code, a slow-releasing relay arranged to be energized when any one of said line relays is deenergized, and receiving means effective when said slow releasing relay is energized to respond selectively to the sequence in which said line relays are deenergized. 25
34. In a remote control system comprising a plurality of normally closed line circuits each including a line relay, means for selectively opening said line circuits in a predetermined sequence to produce a code, a slow releasing relay arranged to be energized when any one of said line relays is deenergized, and receiving means controlled by a front contact of said slow releasing relay and selectively responsive to the sequence in which said line relays are deenergized. 30
35. In combination, a stretch of railway track divided into a plurality of sections, a central office having a plurality of indicators one for each section, a plurality of normally closed line circuits extending along said stretch of track, a transmitter at each section for briefly interrupting said line circuits singly or in combination in a definite sequence to produce a distinctive code, and receiving means responsive to the sequence of interruption of said line circuits to selectively control said indicators. 35
36. In combination, a stretch of railway track divided into a plurality of sections, a central office having a plurality of indicators one for each section, a plurality of normally closed line circuits extending along said stretch of track, a 40
- 70
- 75

transmitter at each section for briefly interrupting said line circuits singly or in combination in a definite sequence to produce a distinctive code, and receiving means responsive to the sequence of interruption of said line circuits to select the indicator corresponding to a particular station in accordance with the code transmitted over said line wires.

37. In combination, a stretch of railway track divided into a plurality of sections, a central office having a plurality of indicators one for each section, a plurality of normally closed line circuits extending along said stretch of track, a transmitter at each section for briefly interrupting said line circuits singly or in combination in a definite sequence to produce a distinctive code depending upon traffic conditions in the associated section, and receiving means responsive to the sequence of interruption of said line circuits to select the indicator corresponding to the operating transmitter and to control such selected indicator selectively in accordance with the code transmitted over said line wires.

38. In combination, a stretch of railway track having a series of traffic governing devices distributed along the stretch, a plurality of line circuits extending along said stretch, a transmitter for each device for briefly interrupting said line circuits singly or in combination in a definite sequence to produce a distinctive code depending upon the condition of the associated device, a central office having a plurality of indicators one for each said device, and receiving means responsive to the sequence of interruptions in said line circuit during each code for controlling the indicator for a particular device in accordance with the character of the code received.

39. In combination, a stretch of railway track having a series of traffic governing devices distributed along the stretch, a plurality of line circuits extending along said stretch, a transmitter for each device set into operation by a change in the condition of the corresponding device to briefly interrupt said line circuits singly or in combination in a definite sequence to produce a distinctive code depending upon the condition of the associated device, a central office having a plurality of indicators one for each said device, and receiving means responsive to the sequence of interruptions in said line circuit during each code for controlling the indicator corresponding to the device which initiated the code in accordance with the character of such code.

40. In combination, a stretch of railway track having a series of traffic governing devices distributed along the stretch, a plurality of line circuits extending along said stretch, a transmitter for each device set into operation by a change in the condition of the corresponding device to briefly interrupt said line circuits singly or in combination in a definite sequence to produce a distinctive code depending upon the condition of the associated device, a central office having a plurality of indicators one for each said device, receiving means responsive to the sequence of interruptions in said line circuit during each code for controlling the indicator corresponding to the device which initiated the code in accordance with the character of such code, and means for preventing the simultaneous operation of two of said transmitters.

41. In combination with a stretch of railway track having a series of traffic governing devices distributed along the stretch, a central office having a plurality of movable levers one for each said

device, a plurality of line circuits extending from said office along said stretch, a transmitter at said office set into operation by the operation of any said lever to briefly interrupt said line circuits singly or in combination in a definite sequence to produce a distinctive code depending upon the particular lever which was operated and the position into which such lever was operated, and receiving means for each said device responsive to the sequence of interruptions in said line circuits to control the particular device associated with the operated lever in accordance with the received code.

42. A centralized traffic controlling system for railroads, comprising a control office and a station, line wires connecting said office and station and affording a plurality of channels of communication between said office and station, means at the office and at the station for creating a series of code elements by modifying the electrical conditions of said channels individually or in combination, and receiving means at the office and at the station each selectively responsive to said elements and to the sequence in which such elements occur in a code transmitted from the other end of such line wires.

43. A centralized traffic controlling system for railroads, comprising a control office and a station, line wires connecting said office and station and affording a plurality of normally closed and energized channels of communication between said office and station, means at the office and at the station for briefly interrupting said channels individually or in combination to produce a series of code elements, and receiving means at the office and at the station each selectively responsive to the particular channel interrupted during a code element and to the sequence of such elements in a code transmitted from the other end of such line wires.

44. In a remote control system a plurality of normally closed line circuits extending from a despatcher's office through a plurality of line stations in series, means at the office for opening said circuits selectively in a definite sequence to produce a code, transmitting means at each station effective when operated to open said circuits selectively in a definite sequence, starting apparatus for initiating operation of said transmitting means, and means at each station responsive to the opening of any line circuit to prevent operation of said starting apparatus for a measured time interval.

45. In a remote control system, a plurality of normally closed line circuits each including a line relay, transmitting means effective when operated to open said line circuits selectively in a definite sequence to produce a complete code of separate code elements, a slow releasing checking relay arranged to be energized when any of said line relays is deenergized, means effective when said checking relay is open to initiate operation of said transmitting means, and means requiring said checking relay to be closed to permit the completion of the operation of said transmitting means.

46. In a remote control system, a plurality of normally closed line circuits each including a line relay, transmitting means effective when operated to open said line circuits selectively in a definite sequence to produce a complete code of separate code elements, a slow releasing checking relay arranged to be energized when any of said line relays is deenergized, means effective when said checking relay is open to initiate operation

of said transmitting means, and means requiring said checking relay to be closed to permit the completion of the operation of said transmitting means.

5. 47. In a remote control system, a plurality of normally closed line circuits each including a line relay, transmitting means effective when operated to open said line circuits selectively in a definite sequence to produce a complete code of separate code elements, a first slow releasing checking relay arranged to be energized when any of said line relays is deenergized, a second checking relay arranged to be energized when all said line relays are energized, means controlled by a back contact of said first checking relay and a front contact of said second checking relay for initiating the operation of said transmitting means, and means controlled by front contacts of both said checking relays for completing the operation of said transmitting means.

48. In a remote control system, a plurality of normally closed line circuits each including a line relay, transmitting means effective when operated to open said line circuits selectively in a definite sequence to produce a complete code of separate code elements, a first slow releasing checking relay arranged to be energized when any of said line relays is deenergized, a second checking relay arranged to be energized when all said line relays are energized, means controlled by a back contact of said first checking relay and a front contact of said second checking relay for initiating operation of said transmitting means, and means selectively responsive to the character of the first element of the resulting code for completing the operation of said transmitting means.

49. In a remote control system, a plurality of normally closed line circuits each including a line relay, means for selectively opening said line circuits in a definite sequence to produce a complete code of separate code elements, receiving means selectively responsive to said code, a slow releasing checking relay arranged to be energized when any of said line relays is deenergized, a device selectively responsive to the first element of a code, and means controlled by said checking relay and by said device for controlling said receiving means.

50. In a remote control system, a plurality of normally closed line circuits each including a line relay, means for selectively opening said line circuits in a definite sequence to produce a complete code of separate code elements, receiving means selectively responsive to said code, a slow releasing checking relay arranged to be energized when any of said line relays is deenergized, a

device selectively responsive to the first element of a code, and means controlled by a front contact of said checking relay and by said device for controlling said receiving means.

51. In a remote control system, a plurality of normally closed line circuits each including a line relay, transmitting means for selectively opening said line circuits in a definite sequence to produce a complete code of separate elements, a repeating relay arranged to be energized only when all of said line relays are energized, a slow release checking relay controlled by said repeating relay, and means controlled by said repeating relay and said slow release relay for controlling said transmitting means.

52. In a remote control system, a plurality of normally closed line circuits each including a line relay, means for selectively opening said line circuits in a definite sequence to produce a complete code of separate elements, receiving means selectively responsive to said code, a repeating relay arranged to be energized only when all of said line relays are energized, a slow release checking relay controlled by said repeating relay, and means controlled by said slow release relay for controlling said receiving means.

53. Remote controlling apparatus comprising a plurality of transmitting relays, a plurality of line circuits each including a contact of an individual one of said transmitter relays and a contact of an additional transmitter relay which controls all said line circuits, and means for operating said transmitter relays selectively in a predetermined sequence to produce a code.

54. In combination with a plurality of line circuits extending between two spaced points, a plurality of transmitter relays at each point each having a contact included in a different one of said line circuits, an additional transmitter relay at each point having a contact in each of said line circuits, and means at each point for selectively operating the transmitter relays at such point in a predetermined sequence to transmit a code to the other said point.

55. In a remote control system of the code type, a plurality of code setting relays, code transmitting means for producing different codes, each made up of a series of code elements, means for setting said transmitting means into operation, means responsive to the first element of a code produced by said transmitting means for operating a selected code setting relay, means controlled by said code setting relay for determining certain elements of the code after said first element, and other means for determining the remaining elements of said code.

ALFRED B. MILLER.
